UNITED STATES PATENT OFFICE

IRVING H. PECK, OF DERBY, CONNECTICUT, ASSIGNOR TO THE STERLING PIN COMPANY,
OF DERBY, CONNECTICUT

HAIRPIN

Application filed September 11, 1928. Serial No. 305,208.

This invention relates to a hairpin and more especially to a hairpin suitable for use with short or bobbed hair, and designed to frictionally grip and hold the hair notwithstanding its short length.

Generally speaking, the invention relates to a hairpin or clip wherein a pair of resilient cooperative legs are provided between which the hair is received and held, and has for its primary object a device of this character in which the hair is more efficiently and comfortably held than in previously known devices for similar purposes.

A further object of the invention is to provide a hairpin or clip of the above character wherein the hairpin may be readily brought into engagement with the hair without any danger of scratching or cutting the scalp.

A still further object of the invention is to provide a hairpin or clip of the above description in which the hair may be gripped in an even manner throughout the length of the clip.

Another object of the invention is to provide a clip of the above character which when in use is substantially invisible.

To these and other ends, the invention consists in the novel features and combination of parts to be hereinafter described and claimed.

In the drawings:

Fig. 1 is a view, in elevation, of a clip embodying the features of my invention;

Fig. 2 is a plan view of the same;

Fig. 3 is a sectional view along line 3—3 of Fig. 1; and

Fig. 4 is a sectional view along line 4—4 of Fig. 1.

Referring now to the drawings in which I have illustrated my invention by showing a preferred embodiment of the same, the reference numeral 10 indicates, in general, the improved hairpin or clip which, as shown, is made of a single length of suitable resilient material bent at an intermediate point 11 to form two legs 12 and 13 between which the hair is received and held, the leg 13 being somewhat shorter than the leg 12, for a purpose to be hereinafter described.

The leg 12 is flattened throughout the

greater portion of its length, as at 14, and is relatively straight, while the other or short leg 13 is of circular cross-section substantially throughout its length and is crimped to form corrugations or waves 15 which assist in holding the hair. Leg 13 is separated from leg 12 a substantial distance adjacent the bend 11, and is then directed toward leg 12 until at 16 the legs are in contact, leg 13 being relatively straight at this point. The terminal portion of leg 13, which is flattened, as at 17, diverges outwardly from leg 12 and is of substantially the same width as the flattened portion of leg 12. The ends of both legs are rounded or curved, as at 18 and 19.

In use, the leg 12 may be applied to the head and the clip pushed or thrust into the hair it is desired to confine. The hair is guided along the extended end of leg 12 until it is trapped between the diverging outer ends of the legs and then passes between legs 12 and 13 separating the latter. Owing to the fact that the legs are in contact at a point substantially adjacent their ends and diverge from one another towards the bend 11, it will be apparent that the hair, once it has passed the point 16, does not meet any markedly increased resistance, as is the case with the usual clip, wherein the legs are in contact throughout their length, but readily passes between the legs, which when the hair is in place therebetween, exert a substantially uniform pressure thereon throughout the length of the clip.

By reason of the fact that one of the legs is flat and of relatively greater width than the other, it is apparent that the legs may be displaced laterally to a considerable extent without reducing their cooperativeness, in holding the hair. The rounded ends ensure that the clip will glide smoothly over the scalp without any danger of scratching or cutting the latter, while the use of wire or material of circular cross-section in forming the clip ensures that the exposed parts, herein in the leg 13, will be as invisible as it is possible to make these parts.

While I have shown and described a preferred embodiment of my invention, it will

be understood that it is not to be limited to all the details shown, but is capable of modification and variation within the spirit of the invention and the scope of the appended claims.

5. What I claim is:

1. A hairpin or the like having a pair of resilient legs between which hair may be received and gripped, one of said legs being of circular cross-section throughout the greater part of its length and the other of said legs being relatively flat throughout the greater part of its length.

10 2. A hairpin or the like made of a single piece of material bent at an intermediate point to form a pair of resilient legs between which hair may be received and gripped, said piece of material being initially of circular cross-section, one of said 15 legs being of the initial circular cross-section throughout the greater part of its length and the other of said legs being flattened throughout the greater part of its length to provide a part of greater width 20 than the leg of circular cross-section.

25 3. A hairpin comprising a single piece of material folded intermediate of its ends to form two legs which cooperate to hold hair therebetween, one of said legs being of round cross-section throughout a considerable portion of its length, and the other of said legs being of rectangular cross-section throughout a considerable portion of its length and wider than the first leg.

30 35 4. A hairpin comprising a single piece of material folded intermediate of its ends to form two legs, one of said legs being of round cross-section and provided with crimps, and the other leg presenting a substantially straight flat inner surface, extending from the end of said second leg toward the fold, but stopping short of the fold.

40 45 5. A hairpin or the like, comprising a single piece of resilient material folded intermediate its ends to form two legs which cooperate to hold hair therebetween, one of said legs being flat and the other of said legs being of round cross-section throughout a substantial portion of its length and in contact with the flat leg adjacent their ends and diverging outwardly therefrom towards the fold and towards the ends of the legs.

50 55 6. A hairpin or the like, comprising a single piece of resilient material folded intermediate its ends to form two legs which cooperate to hold hair therebetween, one of said legs being of round cross-section throughout a substantial portion of its length, the other of said legs being straight and flat and of greater width than the leg of round cross-section, said legs being in contact adjacent their ends and diverging outwardly from one another towards the fold and towards their ends.

7. A hairpin or the like, comprising a single piece of resilient material folded intermediate its ends to form two legs which cooperate to hold hair therebetween, one of said legs being longer than the other, the short leg being of round cross-section and the long leg being straight and flat and of greater width than the short leg, said legs being in contact with one another adjacent their ends and diverging outwardly from one another towards the fold and towards their ends, the short leg being provided with a flattened end beyond the point of contact between the legs.

70 75 8. A hairpin or the like, comprising a single piece of resilient material folded intermediate its ends to form two legs which cooperate to hold hair therebetween, one of said legs being longer than the other, the short leg being of round cross-section and the long leg being straight and flat and of greater width than the short leg, said legs being in contact with one another adjacent their ends and diverging outwardly from one another towards the fold and towards their ends, the short leg being provided with a flattened end beyond the point of contact between the legs, the ends of both legs being rounded.

80 85 90 95 100 105 110 115 120 125 130 9. A hairpin comprising a single piece of material folded intermediate of its ends to form a long leg and a short leg, said long leg having a hair-gripping portion of rectangular cross-section at and for some distance rearwardly from its free end, said short leg being substantially in contact with said long leg at a point inwardly from the free end of said short leg, and being of rectangular cross-section and spaced from said long leg at and adjacent the free end of said short leg, said short leg being of round cross-section for a distance from its contact point with the long leg in the direction of the fold.

10. A hairpin comprising a single piece of material folded intermediate of its ends to form two legs, one of said legs being of greater width than thickness and having a flat inner face extending throughout the major portion of its length, the other leg presenting a rounded inner face opposing the first leg, a portion of said second leg being of substantially less width than the first and said leg contacting with the inner face of said first leg.

In witness whereof, I have hereunto set my hand this 6th day of September, 1928.

IRVING H. PECK.
